Patented Oct. 9, 1962

193,769

ANIMAL SHIPPING CRATE

William S. Kerr, Portland, Oreg. (3825 SE. 113th Ave.,
Multnomah, Oreg.), and Milton F. Taylor, 6026 NE.
35th Place, Portland, Oreg.

Filed Apr. 11, 1960, Ser. No. 60,130

Term of patent 14 years

(Cl. D12—2)

FIGURE 1 is a front perspective view of an animal shipping crate comprising one embodiment of our new design;

FIGURE 2 is a rear elevational view of the embodiment of FIGURE 1;

FIGURE 3 is a front perspective view of a second form of our new design;

FIGURE 4 is a side elevational view of the embodiment of FIGURE 3; and

FIGURE 5 is a rear elevational view of the embodiment of FIGURE 3.

The undisclosed side of the crate of FIG. 1 is the same in appearance as the side shown.

The undisclosed side of the crate of FIG. 3 is substantially the same in appearance as the side shown.

We claim:

The ornamental design for an animal shipping crate, as shown and described.
